(57) CLAIM

The ornamental design for a handcuff restraining apparatus, as shown and described.

DESCRIPTION

FIG. 1 is perspective view of a handcuff restraining apparatus having a pair of bracelet members coupled to a coupling member, showing my new design;

FIG. 2 is a top plan view of FIG. 1 thereof;

FIG. 3 is a bottom plan view of FIG. 1 thereof;

FIG. 4 is a front elevation view of FIG. 1 thereof, with the rear elevation view being a mirror image thereof;

FIG. 5 is a first side elevation view of FIG. 1 thereof, with a second side elevation view being a mirrored image thereof;

FIG. 6 is a perspective view of another embodiment of FIG.

1 thereof, without the front face of the coupling member having inwardly tapered end regions;

FIG. 7 is a rear elevation view of FIG. 6 thereof; and,

FIG. 8 is a first side elevation view of FIG. 6 thereof, with a second side elevation view being a mirrored image thereof.
